[57] CLAIM

The ornamental design for a detachable butt grill for a grapple arch, substantially as shown and described.

DESCRIPTION

FIG. 1 is a top plan view of a detachable butt grill for a grapple arch showing my new design;

FIG. 2 is a front elevational view thereof;

FIG. 3 is a side elevational view thereof; and
FIG. 4 is a front elevational view thereof, the grapple arch being shown in broken lines for illustrative purposes only.

FIG. 1

FIG. 2

FIG. 4

FIG. 3
